UNITED STATES PATENT OFFICE.

SAMUEL P. BENNETT, OF SAN FRANCISCO, CALIFORNIA.

FLUID DOUBLE-ACTION SHOCK ABSORBER.

Application filed September 24, 1924. Serial No. 739,618.

To all whom it may concern:

Be it known that I, SAMUEL P. BENNETT, a citizen of the United States, and a resident of the city and county of San Francisco, and State of California, have invented certain new and useful Improvements in Fluid Double-Action Shock Absorbers, of which the following is a specification.

10 The present invention relates to shock-absorbers in general, and more particularly to those of double action employing a liquid column to which the initial shock is transmitted, to be gradually released therefrom 15 thereafter through transference of this liquid column through minute openings to a common reservoir from which is established a second liquid column, the common reservoir serving as a supply for replenishing alternately the two liquid columns, which are adapted to operate reciprocally.

Primarily, my invention is designed to operate on the principle of by-passing a liquid under pressure in one cylinder to another cylinder from which the pressure is being released, these cylinders being confined within a common casing containing a common chamber with which both communicate, and each fitted with a piston, 30 these pistons being connected, through link connections, to an operating yoke centrally and pivotally secured, and operable through a lever arm carrying universal connections attached to either a spring or axle of a 35 motor vehicle, the other point of support being that as established between the casing and a section of the vehicle's frame.

The essential features of this invention reside in the method of alternately forcing 40 the liquid, as contained within the casing and received by the cylinders therefrom, from one cylinder to the other through the oscillating action of the yoke and co-related parts and the alternate opening and closing of ball check valves, which are adapted to unseat and allow fluid to enter the cylinders when the pistons are on the up-stroke.

Small ports are formed in the cylinder walls, through which liquid from the cylinders is forced into the chamber on the down strokes of the pistons, affording a means whereby relief in pressure may be had of such pressure as may have been transmitted by shock to the liquid columns contained within these cylinders.

A principal object of this invention is to provide a shock-absorber for vehicles, which is reciprocal and positive in action, durable, and of comparatively simple construction.

Another object of the invention is to provide, in a device of the character described, a means whereby road shocks transmitted to the various parts of vehicles, through the wheels coming in contact with obstacles and inequalities, may be reduced to a minimum and the life and usefulness of the vehicle greatly increased.

An additional object is to provide a device of the character specified that will positively check and reduce to a minimum all jars and jolts suddenly transmitted to vehicle axles, and, incidentally, allow any excessive pressure, due to sudden compressive action upon the fluid within the cylinders, to be gradually relieved.

Other objects and advantages of my invention will appear with reference to the subjoined specification and accompanying two sheets of drawings, in which:

Figure 1 is an elevation of one of the devices as it appears, as attached to a section of frame and an axle of a vehicle, a portion being shown in section;

Figure 2 is an edge view of the device, showing it full size, with parts broken away for clearness of illustration;

Figure 3 is an elevation with the cap removed, showing the attaching plate, cylinders, pistons and link connections to the yoke, the cylinders being shown in vertical section and indicated by line 3-3 of Figure 4;

Figure 4 is a vertical mid-section taken through the attaching plate, yoke and housing cap, indicated by the lines 4-4 of Figures 2 and 3;

Figure 5 is a detail of one of the pistons and connecting links; and

Figure 6 is a sectional detail of the adjustable ball joint connection between the shock-absorber lever arm and universal connecting rod to the spring.

Referring to the drawings in detail, the device consists of an attaching plate 1, preferably of cast material having a reinforcing rib 2 carrying oppositely disposed perforated attaching ears 3 adapted to fit against the frame 4 of the vehicle and secured thereto by means of bolts 5. This attaching plate

is provided with a pair of integrally formed cylinders 6 and 7 having bores 8 and 9 extending from the upper ends thereof to near the lower ends 10 and 11. A supporting boss 12 is centrally arranged upon the attaching plate 1 and extends outwardly therefrom and is turned to form a revolvable fit for a stub shaft 13 having a bore 14 adapted to fit snugly upon the boss 12. This 10 stub shaft carries a hub 15 having an integrally formed yoke 16 extending upwardly therefrom and terminating in oppositely disposed arms 17 and 18.

The yoke 16 is substantially in the form 15 of an "anchor" and the arms 17 and 18 thereof terminate slightly above the cylinders 6 and 7 when the yoke is in neutral position as shown in Figure 3. The yoke 16 and stub 13 are free to oscillate upon the boss 12 and the arms 17 and 18 thereof are connected by means of furcated links 19 and 20 to pistons 21 and 22 by means of pins 23, 24, 25 and 26, the pistons 21 and 22 forming sliding fits within the bores 8 and 9 of the cylinders 6 and 7. Leather cups 27 and 28 are secured to the under faces of the pistons 21 and 22 by means of screws and washers 29 and 30 and form a tight fit within the bores 8 and 9 of the cylinders.

20 The lower ends 10 and 11 of the cylinders 6 and 7 are provided with inlet ports 31 and 32 having halved ball checks 33 and 34 adapted to seat therein and held against continued inward movement by means of keys 35 and 36. Relief valves 37 and 38 are tapped into the inner faces of the cylinders 6 and 7 and comprise outlet ports 39, communicating with ports 40, and closed by ball checks 41, held seated by means of coil springs 42, adjustably held in place by means of screw plugs 43. These relief valves are provided in order to relieve excessive pressure accumulated within the cylinders and may be set to relieve this pressure at 45 from five hundred to one thousand pounds, or any other pressure desired.

The attaching plate is of substantially inverted U-shaped configuration and is provided with a series of drilled holes 44 spaced around its outer edge 45 and against which a housing cap 46 is adapted to fit and be secured tightly thereagainst by means of cap screws, or the like, 47 which extend through the holes 44 and are tapped into the bead 48 formed around the outer edge of the housing cap 46. The housing cap 46 is of cast material and is of substantially the same configuration as the attaching plate 1 and is provided in its outer wall 49 with a centrally arranged boss 50 having a bore 51 through which the stub shaft 13 is journaled and aligned with the boss 12.

55 The inner face of the boss 50 is bored out to form a stuffing box 52 adapted to receive packing 53 and the stub shaft 13 carries a

packing ring 54 which bears against the outer face of the hub 15 and maintains and protects the packing within the stuffing box 52 and forms a leak-proof fit between the packing and stub shaft 13.

60 The cylinders 6 and 7 are provided with minute outlet ports 55, 56 and 57, the ports 55 and 56 in the cylinder 6 are of smaller diameter than the port 57 formed in the cylinder 7 and these ports tend to release the fluid content within the cylinders and allow the pistons to move slowly as the fluid is exhausted through these ports on the alternate downward stroke of the pistons 21 and 22.

An operating arm 58 is keyed to the outer end of the stub shaft 13 and held in position by means of a washer 59 and screw 60. This arm extends outwardly beyond the housing cap 46 and is curved slightly as indicated in Figure 2 and terminates in a head 61 into which a ball 62 is tapped. The ball 62 carries an adjustable socket member 63 fitted upon the upper end of a connecting rod 64 which connects the arm 58 to the spring and axle 65 by means of a second ball and socket joint 66, as clearly shown in Figure 1.

A gasket 67 forms a leak-proof fit between the attaching plate 1 and the housing cap 46 and a filling plug 68 is tapped into the wall 49 and provides means whereby the chamber may be partially filled with oil or other fluid.

65 In Figure 3 the device is shown in neutral position or, in a state of equilibrium, the dot and dash position indicating the extreme upward movement of the operating arm 58 and down stroke of the piston 21 and up-stroke of the piston 22.

The fluid level within the chamber is kept at all times above the open ends of the cylinders and is bypassed through the ports 55 and 56 of the cylinder 6 thence through the port 32 and check valve 34 of the cylinder 7 and vice versa.

70 Having thus described and illustrated my invention in its preferred form I wish it understood that the same may be modified as practice suggests without departing from the spirit and scope of my invention as set forth in the following claims:

Claims:

1. A device of the character described, comprising an attaching frame and suitable housing therefor forming an oil chamber, of a plurality of cylinders mounted upon said frame, a pivotal yoke carried by said frame, pistons mounted within said cylinders, link connections between the yoke and pistons, outlet ports formed in said cylinders, check valves mounted in said cylinders, and means whereby the alternate oscillation of said yoke causes the pistons to bypass fluid through the outlet ports of one

cylinder into the check valves of the other cylinder.

2. A device of the character described, comprising an attaching plate, a housing therefor forming a fluid chamber, cylinders carried by said attaching plate, a pivotal yoke carried by said plate, pistons mounted in said cylinders and linked to said yoke, by-pass ports and check valves in said cylinders, and means whereby the oscillating movement of said yoke alternately forces the fluid through the by-pass ports of one cylinder to said chamber and through the check valve of the opposite cylinder.
- 15 3. A device of the character described, comprising an attaching plate, a housing therefor forming a fluid chamber, cylinders carried by said attaching plate, a pivotal yoke carried by said plate, pistons mounted in said cylinders and linked to said yoke, by-pass ports and check valves in said cylinders, and means whereby the oscillating movement of said yoke alternately forces the fluid through the by-pass ports of one cylinder to said chamber and through the check valve of the opposite cylinder; and means for releasing excessive pressure created within said cylinders.
- 20 4. A shock absorber, comprising an attaching plate, a housing therefor forming a fluid chamber, a pivotal yoke adapted to oscillate within said chamber, cylinders formed within said housing and adapted to carry pistons, link connections between said

yoke and pistons, means for alternately bypassing fluid from one cylinder to the other to retard the movement of the pistons and yoke, and means for releasing excessive pressure created by said pistons within the cylinders.

5. A double action shock absorber, comprising a housing forming a fluid supply chamber, cylinders mounted with the chamber adapted to carry a fluid column, means for gradually transferring said fluid column from one cylinder to the other, and means whereby the transference of said fluid column from one cylinder is accomplished more rapidly than from the other.

6. A device of the character described, comprising the combination of a vehicle frame and axle, of a housing mounted upon the frame forming a fluid chamber, an operating arm therefor, a universal connection between said operating arm and vehicle axle, a pivotal yoke mounted within said chamber and connected to said operating arm, cylinders within said housing, pistons mounted to reciprocate within said cylinders and linked to said yoke, means whereby the oscillation of said arm and yoke causes the gradual transference of a fluid column from one cylinder to the fluid chamber and thence to the other cylinder, and means whereby the transference of said fluid column from one cylinder is accomplished more rapidly than from the other.

SAMUEL P. BENNETT.
